(57) **CLAIM**

The ornamental design for a sensing light fixture, as shown and described in the drawings.

DESCRIPTION

FIG. 1 is a front view of the sensing light fixture showing my new design;

FIG. 2 is a back view thereof;

FIG. 3 is a left view thereof;

FIG. 4 is a right view thereof;

FIG. 5 is a top view thereof;

FIG. 6 is a bottom view thereof; and,

FIG. 7 is a perspective view thereof.

In the drawings, the broken lines depict environmental subject matter only and form no part of the claimed design.
